UNITED STATES PATENT OFFICE

160,308

PUMP UNIT

Walter Ernst, Dayton, Ohio, assignor, by mesne assignments, to The Thompson Grinder Company, Springfield, Ohio, a corporation of Ohio

Application April 6, 1948, Serial No. 145,554

Term of patent 14 years

(Cl. D65—1)

To all whom it may concern:

Be it known that I, Walter Ernst, a citizen of the United States, and a resident of Dayton, in the county of Montgomery and State of Ohio, have invented a new, original, and ornamental Design for a Pump Unit, of which the following is the specification, reference being had to the accompanying drawings, wherein:

Figure 1 is an elevational view of a pump unit showing my new design, viewed from the discharge side thereof;

Figure 2 is a top plan view of the pump unit;

Figure 3 is a view similar to Figure 1, but looking in from the opposite end, that is, the power end;

Figure 4 is a view of the right side of Figure 3; and

Figure 5 is a view looking in at the left side of Figure 3.

I claim:

The ornamental design for a pump unit, substantially as shown.

WALTER ERNST.
